UNITED STATES PATENT OFFICE.

MARINUS PETERSEN, OF KENMARE, NORTH DAKOTA.

AEROPLANE.

1,350,938.

Specification of Letters Patent. Patented Aug. 24, 1920.

Application filed October 21, 1918. Serial No. 259,147.

To all whom it may concern:

Be it known that I, MARINUS PETERSEN, a citizen of the United States, residing at Kenmare, in the county of Ward and State 5 of North Dakota, have invented new and useful Improvements in Aeroplanes, of which the following is a specification.

The object of the invention is to provide direction and position controlling elements 10 for use in connection with aircraft of the aeroplane type which shall serve to increase the stability of the machine and facilitate the restoring of the same when disturbed either through adverse or confusing air currents or by reason of errors due to carelessness or miscalculation in manipulation, and also to provide means for increasing the quickness, abruptness and range of evolutions of a craft of this type without essentially 15 modifying the principles of construction which have been approved and put to practical use and also without essentially modifying the method of control which has been adopted and put into practice by, and 20 has become familiar to many hundreds of flying machine operators.

With these objects mainly in view, the invention consists essentially in providing the sustaining plane of the machine, representing the wings, with ailerons which are 25 adapted for deflection under the control of the pilot to produce a variable dynamic resistance to progress in a given direction, as for example parallel with the longitudinal 30 axis of the fuselage. This resistance as to the ailerons at opposite sides of the axis of the machine, or as carried by the respective wings, is relative, or in varying ratios so as to relatively modify the dynamic lifting 35 forces or effect of the wings as well as the relative resistances to forward progress or 40 in the direction of the longitudinal axis. The invention also consists in providing a sustaining wing construction wherein provision is made for diminishing the sustaining 45 effect of the wing which is toward the center of a curve or turn which is to be effected by the machine, and wherein a relative increase of resistance to forward progres- 50 sss is applied to the inner wing relative to the center of such turning movement; in providing means whereby the positive depressing effect due to what may be termed a reverse or counter angle of incidence is applied to the inner wing in the course of turning or describing a curved course; and in

providing a rudder or steering blade having a maximum efficiency in determining the transverse or lateral direction of progress when the machine is tilted or inclined laterally on its longitudinal axis as a center as in banking to follow a curved course or in describing a spiral whether in ascending or descending.

Further objects and advantages will appear hereinafter, and the invention consists moreover in a construction, combination and relation of parts of which a preferred embodiment is hereinafter disclosed, it being understood however that changes in form, proportion and details may be resorted to within the scope of the appended claims without departing from the spirit thereof.

In the drawing:—

Figure 1 represents a plan view of an 75 aeroplane provided with the controlling means embodying the invention.

Fig. 2 is a side view of the same.

Fig. 3 is a front view.

Fig. 4 is a perspective showing the steering and controlling connections which are disposed for manipulation by the operator.

Figs. 5 and 5^a are plan and front views shown diagrammatically, of a machine making a turn or change of course to the right 85 of the operator.

Figs. 6 and 6^a are rear views of a machine moving from a side sliding position to a position of equilibrium and indicating the setting of the ailerons to accomplish their 90 purpose.

Figs. 7 and 7^a are views of a machine as seen respectively in a tail slide and a header, and including indications by darts as to the direction of movement as the machine is 95 righted by the action of the ailerons.

In the illustration of the invention a machine of the bi-plane type has been selected, the upper and lower main sustaining planes 10 and 11 being of the ordinary form, area, 100 construction and relative location, 12 representing the fuselage, 13 the propeller of any preferred type, 14 the rear or tail plane and 15 the rudder or steering blade.

The main (upper) sustaining wings 105 formed by the upper main sustaining plane are provided with ailerons 16 and 17 while the rear or tail plane is provided with corresponding ailerons 18 and 19. Each of these ailerons is adapted to normally occupy 110 a position in the plane of and constitute an element or continuation of the wing by

which it is carried, said ailerons being however connected with the body portion of the wings for deflection from the planes thereof on lines which converge rearwardly 5 of the machine preferably at angles of approximately 45 degrees as shown illustratively by the hinge lines 16^a, 17^a, 18 and 19^a. Any suitable means for independently or jointly deflecting these ailerons in the same 10 or different directions from their positions in the planes of the wings by which they are carried may be employed, but it will be obvious that an upward deflection of an aileron will have two effects,—first the reduction of the effective sustaining area of 15 the wing of which it forms a member with the incident tendency to permit that wing to drop or become depressed if the corresponding aileron at the opposite side of the machine or carried by the companion wing 20 is permitted to retain its normal or extended position in the plane of its wing or the body portion of the wing of which it forms a member, and second—the production of a 25 downward and rearward counter or reverse resistance due to the pressure of the air upon the upper or inner surface of the upwardly deflected aileron which will tend not only to depress the connected wing of the 30 craft but to retard its progress and thus facilitate the turning of the machine from its previous direct forward course toward that side upon which the aileron has been deflected or adjusted. For example, the upward deflection of the aileron 17 as indicated 35 in Figs. 5 and 5^a will have the effect of retarding the forward progress of the right-hand wing of the craft and of depressing said right-hand wing so as to give the machine the tilt or bank necessary to describe 40 a more or less abruptly curved path or turn to the right of the operator as shown by the dotted lines in said figures, the retarding effect or rearward pressure serving to impede the forward progress of the right-hand wing being of advantage owing to the fact 45 that the latter in making such a turn has less distance to travel than the outer wing of which the aileron has been permitted to retain its normal position. Obviously the 50 above effect will be accentuated by a corresponding adjustment with reference to the right-hand aileron of the rear or tail plane, and the corresponding movement of the rudder or steering blade as shown in Fig. 5 55 will have a cooperative action to the same end.

In order that the rudder or steering blade may have a practically uniform effect in 60 guiding or directing the machine whether the latter is on an even keel or is inclined or rolled transversely as in making a turn or describing a curved path, it is preferably mounted or hinged on an oblique line upwardly and rearwardly as shown at 20, a

suitable angle for the line or axis of the hinge being approximately 45 degrees.

An important advantage of the arrangement described resides in the stabilizing effect which may be secured should the machine be tilted or banked excessively so as to assume a position for example such as shown in Fig. 6. The upward deflection of all of the ailerons or of the ailerons at both sides of the machine as shown in said figure, 70 accompanied preferably by the straightening of the rudder or the arrangement thereof in its longitudinal or normal position, whether the engine continues to operate or not, but equally as promptly if the propeller 75 is not in motion, will cause the machine to swing or rock. This will be better understood when it is stated that by reason of the angles of incidence assumed by the ailerons from the position indicated in Fig. 6 in the 80 direction indicated by the darts to the position of stability indicated in Fig. 6^a, and correspondingly an adjustment either downward or upward of the ailerons when the machine is in a tail slide as shown in Fig. 7 85 or describing a header as shown in Fig. 7^a will result in bringing the same to a normal or horizontal position on an even keel. Thus regardless of the position of the machine which may be encountered by an operator, 90 the simultaneous deflection of the ailerons positioned as described will result in restoring the same to a normal position. This is due to what may be regarded as a compound angle of incidence produced by 95 the deflection of the ailerons from the normal planes of the wings on lines which are diagonally disposed and which converge toward the tail end of the machine so as to exert simultaneously both longitudinal and 100 transverse pressures or resistances.

It is desirable as above indicated to provide means for operating the ailerons and rudder or steering blade whereby either independent or joint adjustment thereof may 110 be effected and while various forms of such connections may be employed it will be sufficient for the present purposes to suggest that the post 21 of the steering wheel 22 may be pivoted as at 23, and arranged at 115 an intermediate point in a suitable guide 24, a crank 25 being arranged in operative relation with a bell crank lever 26 or its equivalent connected by lines 27 and 28 with the rudder, while similar lines 29 and 30 are 120 related with the steering or hand wheel so that by the turning movement of the latter in one direction or the other, one or the other of the main wing ailerons is deflected upwardly from its normal position 12 while a corresponding deflection of the rudder or steering blade to the same side of the axis of the machine is produced, said ailerons being yieldingly held in their normal 13 positions, in opposition to the strain which

may be applied thereto through the lines 29 and 30, by lines 31 and 32 having resistance springs 33. The tail plane ailerons may correspondingly be adjusted by means of 5 pedals 34 and 35 connected respectively with said ailerons by lines 36 and 37. When it is desired to deflect the ailerons of both plane wings upwardly as when a side slide is imminent or has begun, the downward 10 movement of the steering wheel about its pivotal axis 23 will secure the desired object and result in the righting of the machine as explained with reference to Figs. 6 and 6^a of the drawing. This bodily downward movement of the steering wheel will result in bringing the rudder or steering blade to a central or normal position by reason of the effect of the crank 25 upon the bell crank lever 26.

20 It will be understood, moreover, that the ailerons of the tail plane serve the usual function and purpose of elevators or elevating means, both being deflected upwardly, either equally or relatively in that connection, according to whether the ascent is to be pursued in a straightaway course or spirally.

It will further be apparent from the foregoing that the hinging of the rudder 15 to 30 the fuselage on an angle of approximately 45 degrees, as indicated by 20, constitutes an important feature of my invention, inasmuch as when the machine is turning and banking, and irrespective of the sharpness of the 35 turning or the leaning of the machine, the

rudder will always stand plumb. From this it follows that under no conditions will the rudder of my improvement act as an elevator—i. e., it will not lean upwardly or downwardly when the machine is in flight. 40

Having described the invention what is claimed is:—

1. An aeroplane having its sustaining and tail wings provided with ailerons mounted for deflection upon diagonal lines convergent rearwardly of the machine, a rudder mounted for lateral deflection upon a line extending upwardly and rearwardly of the axis of the machine, and means for effecting adjustment of said ailerons and 45 rudder.

2. In an aeroplane, a rudder mounted for lateral deflection upon a line extending upwardly and rearwardly of the axis of the machine and having lateral wings and ailerons thereon in combination with a sustaining wing provided with ailerons mounted for deflection upon diagonal lines convergent rearwardly of the machine, means to effect deflection of a sustaining-wing aileron simultaneously with the deflection of the rudder-wing aileron at the corresponding side of the axis of the machine, and means to effect deflection of the other sustaining-wing aileron simultaneously with 55 the deflection of the rudder-wing aileron at the opposite side of said axis. 60

In testimony whereof I affix my signature.

MARINUS PETERSEN.
